PRINTER'S GALLEY

Filed June 11, 1928

UNITED STATES PATENT OFFICE

JAMES EDGAR LEE, OF GRAND HAVEN, MICHIGAN, ASSIGNOR TO THE CHALLENGE MACHINERY COMPANY, OF GRAND HAVEN, MICHIGAN, A CORPORATION OF MICHIGAN

PRINTER'S GALLEY

Application filed June 11, 1928. Serial No. 284,309.

This invention relates to a printer's galley and is particularly concerned with a novel construction of galley which may be utilized for holding a plurality of galleys of type.

5 The invention consists in many novel details of construction and arrangements of parts for providing an effective printer's galley of the type described, on which the usual galley lock may be used with any compartment of the 10 galley to lock the type in place and on which, by reason of the structure of the galley, suitable label holders may be placed one for each section or compartment of the galley to indicate the material contained in any compartment 15 of said galley.

An understanding of the invention for the attainment of the ends stated may be had from the following description taken in connection with the accompanying drawing, in 20 which,

Fig. 1 is a perspective view of the new and improved galley of my invention, and

Fig. 2 is a vertical transverse section through the galley.

25 Like reference characters refer to like parts in the different figures of the drawing.

In the construction of the galley, a tray having a flat bottom 1 is made from sheet metal and at each side edge the metal is 30 turned upwardly to provide vertical sides 2, while at one end the metal is correspondingly bent upwardly to make a front 3, any suitable connection of the sides 2 and the front 3 at the corners being used. In practice a 35 tongue integral with and extending from each of the sides 2 is bent to bear against the other side of the front 3 and is spot welded thereto.

It will be noted that in bending the sides 40 2 upwardly from the bottom 1 an outwardly projecting head 4 is made directly at each side edge of the bottom 1 which extends outwardly beyond the vertical plane of each side 2. This permits sliding the galleys into

45 suitable cabinets or racks for the purpose, having horizontal side guides with which the beads 4 engage and with the fronts 3 of the galleys located at the front of the cabinet.

The same character of bead is made when 50 the front 3 is turned upwardly from the

bottom of the tray but such bead on the front has no particular function other than reinforcement and avoidance of rounded corners against which type may engage.

The space back of the front and between 55 the sides 2 of the galley is divided into a number of galley sections or compartments. Channel bars having horizontal webs 5 and upwardly extending spaced apart vertical legs 6 are laid on the bottom 1 of the galley 60 in properly spaced relation and with the legs 6 parallel to the sides 2, and in such position are permanently secured to the bottom preferably by spot welding thereto.

The galley thus divided into a plurality of 65 compartments is particularly useful not only for storage in a suitable cabinet therefor, but the upstanding sides 2 and legs 6 each are adapted to have the conventional and well known type of galley lock mounted thereon

70 for locking the type located in any section of the galley in place against disarrangement. It is also evident that, as it may at times occur, if it is desirable to reinforce and strengthen or add to the appearance of the 75 galley the sides 2 may be extended and bent outwardly back upon themselves; and in such case the legs 6 will be extended and bent inwardly back upon themselves so that the same

80 galley lock is available for both the sides 2 and the legs 6 in any case. Also each section of the galley is adapted to have a label holder associated therewith, placed on the front 3 of the galley in front of each section as indicated at 7. No specific type of label holder 85 is illustrated and described in the present case as a specific form of label holder is the subject matter of another application for patent bearing Serial No. 284,310, filed June 11, 1928.

90 The invention has proved very practical and satisfactory. It is defined in the appended claims and is to be considered comprehensive of all forms of structure coming within their scope.

I claim:

1. A printer's galley comprising, a bottom, sides extending upwardly from opposite side edges of the bottom, an upwardly extending front at the front edge of said bottom, and a 100

plurality of channels located with the webs thereof in contact with the upper side of the bottom and with the legs thereof extending upwardly, said channels being permanently secured to the bottom and having the legs thereof substantially parallel with said sides.

2. A printer's galley comprising, a member of sheet metal having a horizontal bottom, vertical sides and a vertical front, and a plurality of channels of metal located with their webs against said bottom and with their legs extending vertically upward and parallel to said sides, said webs of the channel being permanently secured to said bottom.

15 3. A printer's galley comprising, a tray of sheet metal having a horizontal flat bottom, sides extending vertically from the side edges of the bottom and a front extending vertically from the front edge of said bottom, 20 means securing adjacent ends of the front and sides of the tray in fixed relation to each other and a plurality of channel members of sheet metal located over the bottom with their front ends bearing against the rear side of 25 the front of the tray and with the webs thereof contacting with the upper side of said bottom and with the legs of said channels extending upwardly and lying substantially parallel to the sides of said tray, said 30 webs and bottom being welded together.

4. A printer's galley comprising, a tray having a horizontal flat bottom, vertical sides at the side edges thereof and a vertical front at the front of said bottom, and a channel 35 located with its web against said bottom, and with its legs extending vertically and parallel to said sides, said web of the channel being permanently secured to said bottom.

5. A printer's galley comprising, a tray 40 having a bottom and vertical sides and division members in the tray above the bottom between and parallel with the sides, each division member comprising two spaced apart vertical sides.

45 In testimony whereof I affix my signature.
JAMES EDGAR LEE.
